WATER CIRCULATOR

Marquis O. Thrush, Peru, Ind., assignor to
H. A. Thrush & Company, Peru, Ind.

Application November 19, 1945, Serial No. 629,503

8 Claims. (Cl. 103—111)

1

This invention relates to water circulators, and more particularly to water circulators for hot water heating systems and the present invention is an improvement over that shown in my Patent No. 2,358,670.

As stated in the above-mentioned patent, water circulators are permitted to operate for long periods of time without attention, and it is important that dependable lubrication be provided. As stated, it is also important that the circulator be inexpensive or competitive in price, and be applicable to homes, regardless of cost.

It is an object of the present invention to provide a circulator of improved, simplified, construction, including a shaft seal with wear on the shaft and leakage minimized, and employing a lubrication which makes attention unnecessary for a period of years.

A further object of the invention is to provide a circulator with the critical parts, including the drive shaft and sealing and lubrication means therefor, constructed as a removable unit and without utilizing non-ferrous metal.

Further objects and advantages of the invention will be apparent from the following description taken in conjunction with the drawings, wherein the figure is a vertical fragmentary section with parts in elevation.

Referring to the drawings, a casing or housing 10 is provided with an inlet 11 and an outlet 12. Within the housing 10 is a wall 13 which defines an impeller chamber 14, and also forms a division between the water flowing into and from the chamber. Water entering the housing through the inlet 11 will be caused to pass above and below the wall 13 and into the chamber 14, from which chamber it can be discharged through the outlet 12.

Mounted on the casing or housing 10 is an oil container or bonnet 15 having arms 16 providing a motor support 17. An impeller shaft 18 extends through the central portion of the bonnet 15, and is adapted to be driven through a flexible coupling (not shown) by a motor (not shown).

On the lower end of the impeller shaft 18 is mounted an impeller 19 by means of a nut 20, or other fastening means. The impeller is preferably made of a pair of sheet metal stampings of disc-like shape with blades 21 struck from the bodies of the same. This particular type of impeller is the subject matter of my Patent No. 2,358,670, and need not be described.

The bonnet 15 has a bottom wall 22 through which the impeller shaft extends, and in order to provide a seal for such shaft where it passes through the bottom wall of the bonnet, a seal assembly is employed.

2

In my previous circulator the bonnet was made from a single casting having a dividing wall between the impeller and lubricant chambers. On the lower side of the dividing wall was an integral seal nose and on the upper side an integral self-lubricating shaft bearing. In the present construction these critical parts, i. e., the self-lubricating shaft bearing and shaft seal with the driving shaft are removable as a unit. This assembly is simpler to apply and remove.

The shaft seal assembly is adapted to fit into a thread opening 23 in the bottom wall 22. This assembly consists of an externally threaded member 24 having a bearing sleeve extending substantially to the top of the bonnet, between which sleeve and the outer wall of the bonnet is provided a reservoir for oil or lubricant. The sleeve 25 is provided with an internal spiral channel 26 extending throughout the length of the sleeve so that oil admitted to this channel around the rotating shaft will upon rotation of the shaft be caused to travel upwardly through the spiral channel and be discharged over the top end of the sleeve so that it may descend by gravity into the oil chamber around the sleeve. Admission of oil from the oil chamber is admitted through passage 27 to the shaft so that it may travel up the spiral passage or channel.

The member 24 is threaded into the casing sufficiently tightly to prevent leakage of oil through the threads of the joint, and therefore the only place left for liquid to escape is around and in close contact with the rotary shaft 18. In sealing the shaft against the passage of fluid, it is necessary to prevent lubricant in the oil reservoir from escaping downwardly past the seal and to prevent liquid circulated in the casing 10 from escaping upwardly past the seal, it being desirable to maintain these fluids apart.

In order to seal against the passage of liquid in either direction through the bottom wall of the bonnet, shaft sealing means is provided. In accomplishing this the threaded member 24 has attached to it a bearing member 28 held in contact with the member 24 by means of a screw thimble 29. The upper and lower opposed surfaces of the bearing member serve as seating surfaces for sealing members 30 of carbon or the like, of which there are preferably two employed, one above and one below the bearing member, and each carbon sealing member in addition to its sealing extremity, which bears against the surface of the bearing member, also has an enlarged portion providing an annular packing receiving recess.

The upper carbon bearing member is resiliently held on the shaft against axial movement in a direction away from the impeller by means of a

spring-ring 32 seated in a groove 18' in the shaft 18. The ring 32 bears against a metal washer 33 within the hollow sleeve portion of the carbon sealing member and presses a sealing gasket 34 tightly against the shaft. The lower carbon sealing member is identical with that just described, but is mounted with its ends reversed on the shaft 18 beneath the bearing member 28. Each carbon sealing member has its seating nose against the bearing member 28, one on each side of the bearing member and with packing in the hollow sleeve portion of the sealing member, the packing held in the upper carbon sealing member by means of the spring-ring 31 bearing against the washer 32. The packing is held in the lower bearing member by means of a helical spring 35, bearing against a similar washer 33 which compresses the gasket 34. The lower end of the spring 35 rests upon the upper surface of the impeller.

It will be readily understood that with the present invention a unitary bearing and sealing assembly is provided, which assembly may be applied by threaded attachment or in other desired manner to the bottom of the bracket casting in fluid-tight contact therewith. The top of the bonnet or oil reservoir is provided with a cover plate 36 frictionally pressed into position, and having in its center carried in a housing 37 a seal ring 38 which fits snugly against the shaft to prevent leakage of oil.

In the operation of the device the bearing with the spiral channel remains stationary, and the shaft rotates therein. Oil is permitted to reach the shaft by means of the channel 27 through the bearing, and this oil will travel or be carried up the channel due to rotation of the shaft until the oil or other lubricant overflows from the upper end of the bearing, and travels or flows by gravity down into the oil reservoir, providing a continuous circulation of oil through the entire bearing. This obviates the necessity of any wicking or capillary material, at the same time keeping the bearing properly lubricated and eliminating undesirable noises due to friction between the shaft and its bearing. The bonnet is provided with an oil level filling plug 39 at a sufficient height that ample oil reserve is obtained, making it unnecessary to refill with oil over a period of years.

The spiral groove in the bearing is relatively shallow, being of a depth only sufficient to hold a quantity of oil slightly in excess of the oil film between the shaft and the adjacent smooth surface of the bearing, so that when the shaft rotates it will exert pressure on the oil in the groove and cause it to travel upwardly in the bore around the shaft, the inherent cohesion between the oil particles or molecules producing a general upward movement of the oil from the well or chamber to the top of the bearing, so that it can overflow and return to the well.

It will be understood that considerable advantage is obtained by having the construction in which the entire lubricating and shaft sealing parts can be assembled in a single unit, in the production of the device, or in the renewal of parts.

Also in the manufacture of the circulator of the present invention the bearing sleeve is of cast iron and non-ferrous metals are not required, thus simplifying and reducing the cost of manufacture.

It will be obvious to those skilled in the art that various changes may be made in the invention

without departing from the spirit and scope thereof, and therefore the invention is not limited by that which is shown in the drawings and described in the specification, but only as indicated in the appended claims.

What is claimed is:

1. A circulator for hot water heating systems designed without the necessity of using non-ferrous metal, and comprising housing defining an impeller chamber and a lubricant chamber removably secured to said housing, one end wall of said lubricant chamber separating said chambers and having an opening therein, a shaft sealing and lubricating assembly disposed in said opening, an impeller shaft rotatably mounted in said assembly, an impeller secured to said shaft and disposed in said impeller chamber, said sealing and lubricating assembly comprising a bearing sleeve disposed in said opening and having a threaded connection with said end wall, said sleeve including a spiral lubricant groove through which lubricant will be forced by the rotation of said shaft, a sealing disk rotatably mounted on said shaft, a screw thimble threadedly received on said sleeve and binding said disk against the end thereof, said sealing disk having a bearing surface at each face, sealing rings on said shaft having sealing surfaces in contact with the sealing surfaces of said disk, each of said sealing rings having an enlarged portion providing an annular recess around said shaft, a gasket in each of said recesses, a wear ring resting on said gaskets, and spring means urging said disks and sealing rings together in a manner to assist in the sealing operation whereby leakage of lubricant and water is prevented and said lubricant chamber, sealing assembly, shaft and impeller may be removed from said housing as a unit thus preventing entry of lubricant into said impeller chamber.
2. A circulator for hot water heating systems designed without the necessity of using non-ferrous metal, comprising a housing defining an impeller chamber provided with an opening, a closure for said opening removably secured to said housing, a shaft sealing and lubricating assembly secured to said closure, an impeller shaft rotatably mounted in said assembly, an impeller secured to said shaft and disposed in said impeller chamber, said sealing and lubricating assembly comprising a bearing sleeve having a threaded connection with said closure, said sleeve including a spiral lubricant groove through which lubricant will be forced by the rotation of said shaft, a sealing disk on said shaft, a screw thimble threadedly received on said sleeve and binding said disk against the end thereof, said sealing disk having a bearing surface at each face, sealing rings on said shaft having sealing surfaces in contact with the sealing surfaces of said disk, each of said sealing rings having an enlarged portion providing an annular recess around said shaft, a gasket in each of said recesses, a wear ring resting on said gaskets, and spring means urging the gaskets and their associated parts together in a manner to assist in the sealing operation whereby leakage of lubricant and water is prevented and said closure, sealing assembly, shaft and impeller may be removed from said housing through said opening as a unit thus preventing entry of lubricant into said impeller chamber.
3. A circulator for hot water heating systems designed without the necessity of using non-ferrous metal, comprising a housing defining an impeller chamber provided with an opening, a closure for said opening removably secured to

said housing, a shaft sealing and lubricating assembly secured to said closure, an impeller shaft rotatably mounted in said assembly, an impeller secured to said shaft and disposed in said impeller chamber, said sealing and lubricating assembly comprising a bearing sleeve having a threaded connection with said closure, said sleeve including a spiral lubricant groove through which lubricant will be forced by the rotation of said shaft, a sealing disk on said shaft, said sealing disk having a bearing surface at each side, sealing rings on said shaft having sealing surfaces in contact with the sealing surface of said disk, and each of said sealing rings having an enlarged portion providing an annular recess around said shaft and a gasket in each of said recesses whereby leakage of lubricant and water is prevented and said sealing assembly, shaft and impeller may be removed from said housing as a unit through said opening thus preventing entry of lubricant into said impeller chamber.

4. A circulator for hot water heating systems designed without the necessity of using non-ferrous metal, comprising a housing defining an impeller chamber provided with an opening, a closure for said opening removably secured to said housing, a shaft sealing and lubricating assembly secured to said closure, an impeller shaft rotatably mounted in said assembly, an impeller secured to said shaft and disposed in said impeller chamber, said sealing and lubricating assembly comprising a bearing sleeve secured to said closure, said sleeve including a spiral lubricant groove through which lubricant will be forced by the rotation of said shaft, a sealing disk on said shaft, holding rings on the opposite sides of said disk and a gasket between each ring and said shaft, and spring means urging the gaskets and their associated parts together in a manner to assist in the sealing operation whereby leakage of lubricant and water is prevented and said sealing assembly, shaft and impeller may be removed from said housing as a unit through said opening thus preventing entries of lubricant into said impeller chamber.

5. A circulator for hot water heating systems designed to eliminate the necessity for using non-ferrous metal, comprising a housing defining an impeller chamber having an opening, a shaft sealing and lubricating assembly secured in said opening, an impeller shaft rotatably mounted in said assembly, an impeller secured to said shaft and disposed in said impeller chamber, said sealing and lubricating assembly comprising a bearing sleeve secured to said housing, said sleeve including a spiral lubricant groove, a sealing member carried by said sleeve, sealing rings on said shaft on opposite sides of the sealing member and having bearing surfaces engaging said sealing member, spring means urging said sealing rings toward and in contact with said sealing member, and gasket means between said sealing rings and said shaft whereby leakage of lubricant and water is prevented and said sealing assembly, shaft and impeller may be removed from said housing through said opening thus preventing entry of lubricant into said impeller chamber.

6. A circulator for hot water heating systems comprising a housing defining an impeller chamber, a lubricant chamber removably secured to said housing, one end wall of said lubricant chamber separating said chambers and having

an opening therein, a shaft sealing and lubricating assembly mounted in said opening, an impeller shaft rotatably mounted in said assembly, an impeller secured to said shaft and disposed in said impeller chamber, said assembly comprising a bearing member having one end threadedly received in said opening, a sealing member carried by said bearing member, sealing rings on said shaft on opposite sides of said sealing member and bearing thereagainst, spring means urging said sealing rings toward and in contact with said sealing member, and gasket means between said sealing rings and said shaft whereby leakage of lubricant and water is prevented and said sealing assembly, shaft and impeller may be removed from said housing as a unit thus preventing entry of lubricant into said impeller chamber.

7. A wall closure member forming a bearing unit for a shaft and a fluid seal between a separable oil chamber and another chamber comprising an insert threaded through the separating wall for said chambers and having at one end a bearing member for said shaft extending into the oil chamber and against its opposite threaded end a sealed bearing disc, clamping means for securing said disk, sealing members on opposite sides of said disk rotatable with said shaft and pressed into fluid tight relationship with respect to said disc and said shaft by resilient spring means whereby leakage of oil from said oil chamber to said other chamber is prevented and said oil chamber, seal and shaft may be removed from said other chamber as a unit.

8. A seal and bearing for a shaft passing through a wall comprising an elongated bearing sleeve threadedly mounted in said wall and rotatably receiving said shaft, a recess in the end of said sleeve, a sealing ring disposed in said recess about said shaft, a gasket disposed in a recess in said sealing ring and engaging said shaft, a sealing disc rotatably mounted on said shaft, one face of said disc engaging said sealing ring, a cap threadedly received on the end of said sleeve and clamping said sealing ring thereagainst, a second sealing ring engaging the opposite face of said sealing disc, a second gasket disposed in a recess in said second sealing ring and engaging said shaft and resilient means engaging said gaskets to urge the same into tight engagement with said shaft and said sealing disc whereby leakage from one side of said wall to the other is prevented.
